RECIPROCATING PUMP

Nelson E. Brigham, Arlington, N. J., assignor to
Worthington Pump and Machinery Corporation,
Harrison, N. J., a corporation of Delaware

Application April 22, 1944, Serial No. 532,271

22 Claims. (Cl. 103—38)

1

This invention relates to reciprocating pumps, and more particularly to a variable capacity, constant speed pump.

An object of the present invention is to provide a constant speed pump employing reciprocating fluid displacement means operated by a novel rotary crank means, and in which the capacity of the pump may be varied from zero to full capacity as a function of variation in the throw of the crank means, with consequent variation in the stroke of the fluid displacement means.

Another object is to provide a pump of the variable capacity, constant speed type wherein reciprocating displacement plungers are employed for pumping the fluid, in which novel means are provided for varying the throw of the respective crank means to vary the stroke of the plungers, with consequent change in the capacity of the pump while the latter is operating at constant speed.

Another object is to provide a pump of the variable capacity, constant speed type employing reciprocating displacement plungers for pumping the fluid, in which eccentrics are adjustably carried by a common driver and connected with the respective plungers for imparting pumping motion thereto, and in which a single control means is employed for simultaneously shifting the eccentrics in like amounts relatively to the axis of the common driver to vary the throw of the eccentrics, with consequent change in the stroke of the displacement plungers.

A further object is the provision of a rotative driver having an eccentric adjustably carried thereby, and in which novel means are employed for adjusting the eccentric relatively to the axis of rotation of the driver to vary the throw of the eccentric.

With these and other objects in view, as may appear from the accompanying specification, the invention consists of various features of construction and combination of parts, which will be first described in connection with the accompanying drawings, showing a reciprocating pump of a preferred form embodying the invention, and the features forming the invention will be specifically pointed out in the claims.

In the drawings:

Figure 1 is a vertical and partial sectional view of a pump in accordance with the present inven-

2

tion, with the pressure fluid and lubricating circuits removed for the sake of clearness.

Figure 2 is an enlarged sectional view of a control cylinder and its piston.

Figure 3 is a transverse sectional view of the pump structure of Figure 1.

Figure 4 is a partial sectional view of a side rod.

Figure 5 is a sectional view taken along the line 5—5 of Figure 7, but at a reduced scale.

Figure 6 is a sectional view taken along the line 6—6 of Figure 7, and also at a reduced scale.

Figure 7 is an enlarged sectional view taken substantially along the line 7—7 of Figure 13.

Figure 8 is a longitudinal sectional view of a pilot valve.

Figure 9 is a transverse sectional view of a valve bushing in which the pilot valve of Figure 8 operates.

Figure 10 is a side view of a portion of the pump frame, a control cylinder and a pressure fluid circuit.

Figure 11 is a fragmentary elevational view of a control bar.

Figure 12 is a face view of an eccentric cross bar.

Figure 13 is an end view of the structure of Figure 10.

Figure 14 is an elevational view of a rotative driver or eccentric shaft, with a portion thereof shown in section.

Figures 15, 16, and 17 are sectional views of crank means or eccentric structures showing the relative positions thereof in a given position of the eccentric shaft of Figure 14.

Figure 18 is a sectional view of the eccentric structure of Figure 15, but illustrating the eccentric structure in its full throw position in contradistinction to the zero throw position of Figure 15.

Figure 19 is a sectional view taken along the line 19—19 of Figure 14, but with certain parts removed for the sake of clearness.

Figure 20 is a view taken substantially along the line 20—20 of Figure 1.

Referring more particularly to the drawings, Figures 1 and 3 illustrate a pump frame 1 upon which is mounted a cylinder block 2 and made secure by bolts 3. The cylinder block 2 is provided with a plurality of cylinders or plunger chambers 4 arranged in a straight line and spaced longitudinally of the cylinder block 2 when viewed according to Figure 1. Three plunger chambers are embodied in the cylinder block of Figure 1, but any desired number of plunger chambers may

be employed, depending upon the specific work for which the pump is designed. All the plunger chambers are arranged vertically, and each chamber is provided with a reciprocating work element or displacement plunger 5 which extends some distance above the cylinder block. Each displacement plunger 5 has its upper end bolted at 6 to an upper crosshead 7, the reciprocation of which imparts reciprocatory motion to the plunger. The respective displacement plungers 5 are individually driven, but in a predetermined and unvarying timed order.

Two side rod assemblies 8 are associated with each upper crosshead 7. The side rod assemblies 8 parallel their respective vertically positioned displacement plungers 5, and each side rod comprises a work rod 9 which is bolted at 10 to one end of its associated upper crosshead 7. All the side rod assemblies 8 are of like construction, and each rod 9 is enclosed in telescopically related tubes 11 and 12. In Figure 4, the tube 11 is secured to a collar 13 which is clamped to the upper crosshead 7 through tightening of the nut 10. External threads 14 are provided on the tube 12 for the reception of a nut 15 which is threaded into engagement with a plate-like body 16, the latter being clamped to the upper end of the cylinder block 2 through tightening of the nuts 15 on the respective tubes 12. The tubes 12 are threaded into bores 17 in the cylinder block 2, as at 18, the bores 17 being of such diameters as to freely accommodate their respective work rods 9. All the work rods 9 extend downwardly to positions inside the frame 1, and the work rods are arranged in parallel relationship, one with the other and with the displacement plungers 5.

Each pair of rods 9 is attached to a crosshead 19. The crossheads 19 are contained in the frame 1 and are guided for reciprocation by crosshead guides 20 formed integrally with the frame. Crank means or eccentric devices 21 are operatively connected with the respective crossheads 19 for imparting reciprocatory motion to the crossheads and similar motion to the displacement plungers 5 through the medium of the work rods 9. While the crossheads 19 are individually driven by their respective crank means 21, the crossheads 19 maintain a predetermined operating order devoid of any phase change to maintain the unvarying operating order of the displacement plungers. All the crank means 21 are mounted on an eccentric shaft or driving shaft 22 which is supported in bearings 23, the latter being in turn supported by the frame 1.

In Figures 1 and 2, the chambers 4 have communication with cross passages 24, each cross passage having communication with a suction passage 25 and a discharge passage 26. All the suction passages 25 have communication with a common inlet chamber 27, while the discharge passages 26 have communication with a common discharge chamber 28. A threaded opening 29 is provided in the cylinder block 2 for connection with a suitable fluid inlet pipe (not shown) to supply fluid to be pumped to the inlet chamber 27, and a threaded opening 30 is also provided in the cylinder block 2 for connection with a suitable fluid discharge pipe (not shown) for receiving pumped fluid from the discharge chamber 28.

Valve seats 31 are contained in the respective suction passages 25, and similar valve seats 32 are contained in the respective discharge passages 26. Figure 3 shows a suction wing valve 33 operatively associated with one of the seats 31,

which valve is yieldingly biased to a closed position by a compression spring 34 abutting that valve and a plug 35 threaded into a bore 36 in the cylinder block 2. Thus the cross passages 24 are isolated one from the other so far as operation of the respective displacement plungers 5 is concerned, even though all the passages 25 have communication with the one inlet chamber 27. Similar discharge wing valves 37 are operatively associated with the respective seats 32, which valves are yieldingly biased to a closed position by compression springs 38. The springs 38 are interposed between the valves 37 and plugs 39 threaded into bores 40 in the cylinder block 2. The cross passages 24 are also isolated one from the other on the discharge side of the pump so far as the operation of the displacement plungers 5 is concerned.

When viewing Figure 3, an upward stroke of the plunger 5 causes the valve 31 to move off its seat to permit fluid from the inlet chamber 27 to flow into the chamber 24. Upon downward movement of the plunger 5, the valve 37 is caused to lift off its seat 32 to permit the fluid in the cross passage 24 to flow into the discharge chamber 28.

Accordingly, the suction valves 33 prevent reverse flow of fluid from the cross passages 24 back to the inlet chamber 27 on the down strokes of the respective displacement plungers 5. In the same manner, the valves 37 prevent reverse flow of the fluid from the discharge chamber 28 back to the cross passages 24 on the up stroke of the respective displacement plungers 5.

The eccentric shaft 22 is of hollow formation and is provided with three bodies 41 spaced longitudinally of the shaft. Each body 41 comprises a part of one of the crank means 21, and all the crank means 21 are of like construction. In Figure 3, the body 41 comprises an integral part of the eccentric shaft 22, and the body is eccentrically located with respect to the axis of the shaft, which is best illustrated in Figure 14. The body 41 in Figure 3 serves as a mount for an eccentric disc 42, which is adjustable on the body to vary the crank throw, and which is connected with an eccentric strap 43 forming a part of a connecting rod 44. This connecting rod is drivingly connected with one of the crossheads 19 by a crosshead pin 45, so that when the eccentric disc 42 is positioned eccentrically with respect to the driving shaft 22 reciprocatory motion will be imparted to the crosshead. The eccentric disc 42 in Figure 3 is so positioned that it is co-axial with the driving shaft 22, at which time no motion is imparted to the crosshead 19 even though the driving shaft 22 is rotating at normal speed.

Figures 15, 16, and 17 show the relative positions of the crank means 21 in a given position of the driving shaft 22, with the bodies 41 spaced 120° apart radially of the eccentric shaft. Each eccentric disc includes an opening 46 for accommodating its respective body 41, and the openings 46 are defined by two opposed flat faces 47 and 48 and two opposed faces 49 curved concentrically of the axis of the eccentric disc 42. Each body 41 is provided with a flat face 50 which lies in face to face engagement with the face 47 of its associated eccentric disc 42. A second flat face 51 is also provided on each body 41, the faces 51 lying in parallelism with the faces 50 on the respective bodies. Thus all the faces 47, 48, 50, and 51 are parallel one with the other. Curved end faces 52 are also provided on the bodies 41, and

the eccentric discs 42 lie in the planes of their respective bodies 41.

In Figures 15, 16, and 17, the crank means 21 are adjusted to their zero throw positions, at which time the axes of all the eccentric discs 42 are co-axial with the eccentric shaft 22. Figure 18 illustrates one of the eccentric discs 42 adjusted to its maximum throw position. Means for adjusting the eccentric discs 42 to desired crank throw positions for controlling the stroke of the displacement plungers 5 include eccentric crossbars 53 which lie in face to face engagement with the respective flat faces 48 in the eccentric discs 42. A rib 54 is formed on each eccentric cross bar 53 for engagement inside a correspondingly shaped groove 55 in its associated eccentric disc 42. While the eccentric discs 42 may be shifted relatively to and laterally of the eccentric shaft 22, the eccentric cross bars 53 are restrained from relative movement with respect to their associated eccentric discs.

Flanges 56 are provided on the bodies 41, and the eccentric cross bars 53 lie between the flanges 56 and upon the flat faces 51 on the bodies 41. The flanges 56 are arranged at right angles to the axis of the eccentric shaft 22. Thus the eccentric discs 42 may be shifted for crank throw changing purposes by adjusting the eccentric cross bars 53 to different positions at right angles to the axis of the eccentric shaft 22, since the eccentric cross bars are keyed to their respective eccentric discs 42. With the eccentric discs 42 in the positions of Figures 15, 16, and 17, one face 49 of each eccentric disc lies in engagement with one end face 52 on its associated body 41, and when the eccentric discs 42 are adjusted to their maximum throw positions, the other face 49 lies in engagement with the second end face 52. Thus the faces 49 and 52 constitute stops which precisely position the eccentric discs 42 in their zero and maximum crank throw positions.

All the eccentric discs 42 are shifted simultaneously and in like amounts to change the stroke of the displacement plungers 5. Means for adjusting the eccentric cross bars 53 to shift the eccentric discs 42 comprise a control shaft or rod 57 which is axially slidably in and guided by the eccentric shaft 22. This control rod is recessed at 58 for the reception of racks 59, which racks lie inside the eccentric shaft 22 in parallelism with the axis of the control rod 57, and at right angles to their respective eccentric cross bars 53. The teeth 60 on the racks 59 are in meshing engagement with teeth 61 on their associated eccentric cross bars 53. Figures 14 and 19 illustrate the bodies 41 as being provided with openings 62 for exposing the racks 59, thereby permitting engagement between the teeth 60 and 61. Effective engagement between the two sets of teeth 60 and 61 is made possible by locating the flat faces 51 such with respect to the axis of the driving or eccentric shaft 22 as to intersect a considerable amount of the inside surface of the driving or eccentric shaft. The teeth 60 angle axially with respect to the axis of the control rod 57, the latter being co-axial with the driving or eccentric shaft 22. An angle of approximately 26° has been found satisfactory, although it is to be understood that the invention is not limited to this angle of the teeth and that any degree of angle found practical may be employed, this angle being best illustrated in Figures 11 and 14. The teeth 61 on the eccentric cross bars 53 are correspondingly angled, as shown in Figure 12.

The racks 59 are fixedly secured to the control

rod 57, as by bolts 63 in Figure 1. The racks 59 are made detachable from the control rod 57 to facilitate replacement in case of excessive wear on the rack teeth, the same being true of the eccentric cross bars 53 with respect to their associated eccentric discs 42.

Adjustment of the control bar 57 relatively to and axially of the eccentric shaft 22 imparts corresponding movement to the racks 59. In view of the angle of the teeth 60 and 61, movement of the racks 59 relatively to the eccentric cross bars 53 imparts movement to the eccentric cross bars and the eccentric discs 42, but at right angles to the axis of the eccentric shaft 22. While the eccentric discs 42 are shiftable relatively to the bodies 41, the engaging flat faces 47 and 50 and the eccentric cross bars 53, which are interposed between bodies 41 and the eccentric discs, key or lock the eccentric discs to the shaft 22 for rotation therewith. At the same time the control rod 57 is keyed to the eccentric shaft 22 for rotation therewith, since engagement between the racks 59 and the control rod 57 and the eccentric cross bars 53 prevent relative rotation between the control rod and the eccentric shaft 22, but permit free relative axial movement. The faces 47 and 50 in one crank means 21 are spaced 120° radially from the same faces in an adjacent crank means, and determine the direction of relative radial adjustment of the eccentric discs 42. This 120° spacing is the desirable arrangement in a three-cylinder pump, but other degrees of spacing will work equally well in connection with pumps embodying a different number of cylinders.

While the eccentric cross bars 53 are free to shift laterally of the eccentric shaft 22, the eccentric cross bars are restrained from relative movement longitudinally of the eccentric shaft 22 by the flanges 56. Figure 1 illustrates the eccentric discs 42 and the bodies 41 as being of the same size longitudinally of the eccentric shaft 22. Side plates 64 are bolted at 65 to the ends of the eccentric discs 42, which side plates engage the flanges 56, the eccentric discs 42, and the eccentric straps 43 to hold the eccentric straps and the eccentric discs in assembled relationship with their respective bodies 41. The side plates 64 are recessed at 66, see Figure 20, which facilitates assembly of the side plates, in addition to permitting radial movement of the side plates relatively to the eccentric shaft 22.

In Figure 1, a compression spring 67 is housed in the eccentric shaft 22 and abuts one end of the control rod 57. The other end of the spring 67 abuts a plug 68 threaded into the end of the eccentric shaft 22, this end of the shaft 22 extending to a position exteriorly of the frame 1 for connection with a suitable drive (not shown).

An increased pumping stroke is attained by shifting the control bar 57 against the tension of the spring 67. Means for shifting the control bar 57 to increase the pumping stroke comprises a control mechanism 69, see Figures 1, 2, and 7. In Figure 2, the control rod 57 extends into a control cylinder 70 and is provided with a piston 71 which is slidably contained in the control cylinder. In view of the fact that the control rod 57 rotates as a unit with the driven eccentric shaft 22, suitable bearings 72 are interposed between the piston 71 and the control rod to eliminate rotation of the piston relatively to the control cylinder 70. Increased stroke is obtained by admitting a pressure fluid to the chamber 73 in the control cylinder 70. The pressure of the fluid acts on the piston 71 to impart axial movement

to the control rod 57 against the tension of the spring 67. Decreased stroke is obtained by releasing pressure fluid from the chamber 73, thereby permitting the control rod 57 to be shifted in a reverse direction through the influence of the spring 67.

The pressure fluid may comprise oil such as is employed for lubricating the working parts of the pump as a whole, which permits the pressure and lubricating circuits to be connected with a single oil circulating pump. Oil under pressure is admitted to the chamber 73 through a pipe 74, see Figures 2, 10, and 13. Admission of fluid under pressure to the pipe 74 is controlled by a pilot valve 75, see Figure 7. The pilot valve is located between the pipe 74 and a supply pipe 76, see Figures 10 and 13, which communicates with a gear pump indicated generally at 77. Such pumps are old and well known in the art and need not be described in detail. Suffice it to say that Figure 1 illustrates a gear 78 as being attached to the eccentric shaft 22 and meshing with a gear 79 which drives the pump 77. In Figures 6 and 7, the cylinder 70 extends partly inside a control box 79 which houses the pilot valve 75. A valve bushing 80 is made secure in a bore 81 in a body 82 comprising a portion of the control box 79. The pilot valve 75 is slidably guided in the valve bushing 80, and communication between the pipes 74 and 76 is controlled by the position of the pilot valve 75 inside the valve bushing 80.

The pilot valve 75 is arranged vertically in the control box 79 and is guided at its upper end by a bushing 83 made secure in a bore 84 in the control box 79. That portion of the pilot valve 75 operating in the valve bushing 80 is shaped to provide heads 84 and 85 slidably engaging the inner face of the valve bushing 80, the two heads being separated by a neck 86 of such diameter as to provide an annular space 87 between the neck and the valve bushing 80. In Figure 7, the discharge end of the pipe 76 communicates with a passage 87 in the control box 79, which passage has communication with openings 88 in the valve bushing 80. With the pilot 75 positioned as shown in Figure 7, the head 84 is so positioned as to close the openings 88, thereby preventing fluid under pressure from entering the valve bushing.

The openings 88 comprise three in number, and the valve bushing 80 is additionally provided with three openings 89 and three openings 90. The openings 90 are positioned above the upper face 91 of the body 82, while the openings 89 are located between the two sets of openings 88 and 91. All the openings are of like contour and arrangement. Figure 9 illustrates the valve bushing 80 in cross-section in the plane of the openings 88. A groove 92 extends circumferentially of the valve bushing 80 and in its outer face in the plane of the openings 88, and a similar groove is provided in the valve bushing 80 in the plane of the group of openings 89. Downward movement of the pilot valve 75 in the valve bushing 80 establishes communication between passage 87' in the control box 79 and the annular passage 87 inside the valve bushing. The openings 90 remain closed. At this time, fluid under pressure enters the annular passage 87 and flows outwardly therefrom through a passage 93, see Figure 6, in the body 82. A passage 94 places the passage 93 in communication with the pipe 74, so that pressure fluid will be admitted to the cham-

ber 73 of the control cylinder 70 as long as the head 84 of the pilot valve 75 permits pressure fluid to flow through the openings 88.

The grooves 92 assure free passage of the pressure fluid at all times, and eliminate the necessity of precise positioning of the valve bushing 80 to align one each of the openings 88 and 89 with the passages 87' and 93, respectively. Admission of pressure fluid into the chamber 73 imparts an axial shift to the control rod 57 for increasing the throw of the crank means 21, thus correspondingly increasing the stroke of the displacement plungers 5, the amount of crank throw increase depending upon the amount of pressure fluid admitted to the chamber 73. To decrease the throw of the crank means 21, or to bring the crank means back to their zero throw positions, pressure fluid is bled from the chamber 73. This is accomplished by lifting the pilot valve 75 in the valve bushing 80 sufficiently far to bring the head 75 to an uncovering position with respect to the openings 90. At this time, the spring 67 returns the control rod 57 to or toward the position of Figures 1 and 7, which causes the pressure fluid to reverse its flow in the pipe 74, enter the annular passage 87 and overflow into the control box 79 by way of openings 90.

Means for actuating the pilot valve 75 comprise a floating lever 95, see Figure 7, one end of which is loosely positioned in an opening 96 in the pilot valve 75. This end of the floating lever 95 is connected with the pilot valve by a pivot 97, which causes axial movement to be imparted to the pilot valve through pivotal movement of the floating lever. The other end of the floating lever 95 is loosely connected with a link 98, as by a pivot 99, the link 98 being connected with an arm 100, as by a pivot 101. This arm is keyed to a shaft 102 which is rotatably supported in bores 103 in bodies 104 and 105 formed integrally with the control box 79, see Figure 5. To the shaft 102 is keyed a control lever 106, which lever extends downwardly and is provided with a ball bearing supported roller 107 at its lower end. This roller lies in a circumferential groove 108 in the control rod 57, the roller being confined between the side faces 109 of the groove 108. Thus axial movement of the control rod 57 imparts pivotal movement to the lever 106, such pivotal movement imparting pivotal movement to the arm 100 and the floating lever 95.

To the floating lever 95 is connected a link 110, as by a pivot 112 located at the center of the floating lever. This link is attached to a micro-motion or control member 111 which is actuated by a positioning motor, indicated generally at 112 in Figures 1, 10 and 13. Motors of this type are provided with pilot control switches, indicated generally at 113 in Figure 1, which will meet any stroke requirement of the control member 111. Various types of controls are available to suit the particular type of service for which the pump may be used. Obviously, the present pump may be operated manually.

The throw of the crank means 21 may be increased in desired amounts by moving the control number 111 downwardly a predetermined distance, as when viewing Figure 7, which pivots the floating lever 95 counterclockwise about the pivot 99 as a fulcrum. Counterclockwise movement of the floating lever 95 moves the pilot valve 75 downwardly from its neutral or zero throw position of Figure 7, which uncovers the open-

ings 88. As the head 84 of the pilot valve 75 uncovers the openings 88, pressure fluid flows into the annular space 87, through the openings 89, the passages 93 and 94 of Figure 6, the pipe 74, and into the chamber 73 of the control cylinder 70.

Admission of pressure fluid to the chamber 73 causes the control rod 57 to move axially and shift the racks 59 relatively to the eccentric cross bars 53, with consequent lateral movement of the eccentric discs 42 relatively to the axis of rotation of the eccentric shaft 22, and in crank throw increasing directions. At the same time, such axial movement of the control rod 57 swings the control lever 106 counterclockwise to the dotted line position of Figure 7, as an example, and turns the arm 100 in the same direction, which pivots the floating lever 95 clockwise about the pivot 112 as a fulcrum. Clockwise rotation of the floating lever 95 lifts the pilot valve 75 relatively to the valve bushing 80 and brings the head 84 back to its neutral position, which cuts off the supply of pressure fluid to the control cylinder and prevents further axial movement of the control rod 57.

Return of the pilot valve 75 to its neutral position through clockwise rotation of the floating lever, as upon termination of a crank throw increasing movement of the control rod 57, traps the pressure fluid in the chamber 73 of the control cylinder 70, so that the crank throw will be maintained against the tension of the spring 67 until the pressure fluid is released from the control cylinder. The pressure fluid in the control cylinder is released by lifting the pilot valve 75 from the position of Figure 7, and such release is attained by lifting the control member 111 to elevate the pivot 112, which pivots the floating lever 95 about the pivot 99 as a fulcrum, thereby lifting the pivot 97 and the attached pilot valve 75. Upward movement of the pilot valve 75 shifts the head 85 of the pilot valve to uncover the openings 90, but the openings 88 remain closed because of the head 84.

When the openings 90 are uncovered, movement of the control rod 57 by the spring 67 advances the piston 71 and forces the pressure fluid from the control cylinder, the pressure fluid overflowing into the control box 79 by way of the openings 90. Return movement of the control rod 57 swings the control lever 106 in a clockwise direction, which pivots the floating lever 95 in a counter-clockwise direction about the pivot 112 as a fulcrum, thereby bringing the pilot valve 75 back to its normal position of Figure 7. Return movement of the control rod 57 decreases the crank throw in accordance with the extent of return movement of the control rod.

The actual increase in crank throw is determined by the distance the pivot 112 is moved downwardly from its neutral full line position of Figure 7, which in turn determines the actual stroke of the displacement plungers 5. The pivot 112 remains fixed, except when its position is changed through adjustment of the control member 111; and any downward movement of the pivot 112 pivots the floating lever 95 counter-clockwise about the pivot 99 as a fulcrum. Any downward movement of the pilot valve 75 as an incident to counter-clockwise pivotal movement of the floating lever 95 uncovers the openings 88 to deliver pressure fluid to the control cylinder 70. Since the floating lever 95 is also influenced by movement of the control rod 57, clockwise rotation of the floating lever about

the pivot 112 as a fulcrum brings the pilot valve 75 back to its neutral position when the floating lever 95 has moved in a clockwise direction to the extent of its previous counter-clockwise movement. Accordingly, pivotal movement of the floating lever 95 in one direction as an incident to shifting of the pivot 112 sets the control lever 106 in motion through movement of the control bar 57 for pivoting the floating lever in the reverse direction and to the same extent. Such movement of the pilot valve 75, first in one direction and then in the other, or by a succession of movements in one direction, provides a control valve means which effectively regulates the flow of pressure fluid into and out of the control cylinder for crank throw adjusting purposes.

With the pilot valve 75 in the neutral position of Figure 7, the upper end of the head 84 barely covers the openings 88, and the lower end of the head 85 barely covers the openings 90. Thus the openings 88 start to open immediately upon downward movement of the pilot valve, and the openings 90 start to open immediately upon upward movement of the pilot valve. To assure free movement of the pilot valve 75, even through pressure fluid should accumulate in the bore 81 beneath the pilot valve or above the pilot valve in the bushing 83, a passage 114 passes longitudinally through the valve, which passage communicates with the opening 96 to provide an escape for the pressure fluid which might otherwise interfere with the efficient operation of the pilot valve. Pressure fluid overflowing into the control box 79 has access to the frame 1.

In Figures 10 and 13, a suction oil pipe 115 leads from the frame 1 to the oil pump 77. The oil pressure pipe 76 is connected with a pipe 116 which leads directly to the discharge side of the pump 77. The pipe 116 is branched at 117 and distributed on opposite sides of the frame 1 for supplying lubricant to the crosshead guides 20. Thus the pressure fluid circuit is tapped into the lubricating circuit of the pump, so that the pump 77 provides the oil circulating medium for both circuits.

Referring to Figures 1 and 3, the displacement plungers 5 pass through packing 118 which is confined between plunger throat bushings 119 and plunger glands 120 in the bores 4. Plungers gland rings 121 are interposed between the plunger glands 120 and the packing 118. The plunger glands 120 are threaded through the plate-like body 16, which permits the packing to be placed under the necessary degree of compression.

The control cylinder 70 is bolted at 122 to an end cover member 123, and the latter is bolted at 124 to the frame 1. Hand hole cover plates 125 are bolted at 126 to the sides of the frame 1, and the control box 79 is also provided with a hand hole cover plate 127, which is bolted at 128 to the control box.

While the present pump is ideally suitable for marine service, which requires a constant speed power pump in which the pump capacity may be varied from zero to maximum to meet boiler feed water requirements, the pump is equally suitable for other pumping duties. The operation of the adjustable crank means is smooth throughout their entire crank throw range, and ample lubrication is assured for all parts of the crank means. The side plates 64 are positioned according to Figure 20, and their inner faces are recessed at 129, so that the side plates function as scoops

which fill the spaces in the crank means with lubricating oil.

Any foregoing statements regarding directional movements of the respective parts of the control mechanism 69 define the construction and operation of those parts in accordance with the specific arrangement of the structure as shown in the drawings. Accordingly, such statements are not limitations, since all these parts, as well as other parts of the pump, may be arranged differently, 10 so that the directional movements would be different.

It will be understood that the invention is not to be limited to the specific construction or arrangement of parts shown, but that they may be 15 widely modified within the invention defined by the claims.

What is claimed is:

1. In a variable capacity pump, a cylinder, a reciprocating pumping plunger operating in said cylinder, a rotative driver, adjustable crank means carried by said driver and operatively connected with said plunger, a control rod operatively connected with said adjustable crank for varying its throw to change the stroke of said plunger, a pressure fluid circuit including a control cylinder, a piston on said control rod and operating in said cylinder, valve means for controlling the admission of pressure fluid into said control cylinder for moving said piston and the control rod, and means actuated by movement of said control rod for closing said valve upon admission of a predetermined amount of pressure fluid to said cylinder.

2. In a variable capacity pump, a cylinder, a reciprocating pump plunger in said cylinder, a rotative driver, crank means adjustably mounted on said driver and operatively connected with said plunger, a control rod operatively connected with said crank means for adjusting the crank means to vary its throw and change the stroke of said plunger, a pressure fluid circuit including a control cylinder, a piston on said control rod and operating in said control cylinder, valve means for controlling the admission of pressure fluid into said control cylinder for moving said piston and the control rod, and means actuated by movement of said control rod in predetermined increments for closing said valve to arrest movement of said control rod.

3. In a variable capacity pump, a cylinder, a reciprocating pumping plunger in said cylinder, a rotative driver, adjustable crank means carried by said driver and operatively connected with said plunger, a control rod operatively connected with said adjustable crank means for varying its throw to change the stroke of said plunger upon movement of the control rod, a pressure fluid circuit including control cylinder, a piston on said control rod and operating in said control cylinder, a valve for controlling the admission of pressure fluid into said control cylinder for moving the control rod, a control member, an operating connection between said control member and said valve for opening the valve to admit predetermined quantities of pressure fluid into said control cylinder, and means actuated by movement of said control rod for closing said valve upon admission of a predetermined amount of pressure fluid to said cylinder.

4. In a variable capacity pump, a plurality of cylinders, reciprocating pumping plungers in said cylinders, a drive shaft, eccentrics adjustably mounted on said drive shaft and operatively connected with the respective plungers, a control

rod operatively connected with the eccentrics for varying their throws to change the strokes of the respective plungers upon movement of the control rod, a pressure fluid circuit including a control cylinder, said control rod having a piston operating in said cylinder and controlled in its position by the admission of pressure fluid to the cylinder or the release of pressure fluid therefrom, a valve for controlling the admission of pressure fluid into said cylinder or for releasing the pressure fluid therefrom, a positioning motor actuated means, an operating connection between said positioning motor actuated means and said valve for opening the latter to admit pressure fluid to said control cylinder, and means operatively connecting said operating connection with said control rod for closing said valve upon the admission of a predetermined amount of pressure fluid to said control cylinder.

5. In a variable capacity pump, a cylinder, a reciprocating pumping plunger in said cylinder, a drive shaft, an eccentric adjustably mounted on said drive shaft and operatively connected with said plunger, a control rod operatively connected with said eccentric for adjusting the latter relatively to said drive shaft through movement of the control rod, a pressure fluid circuit including a cylinder, a piston on said control rod operating in said control cylinder for moving the control rod through admission of pressure fluid to the control cylinder or the release of pressure fluid therefrom, a valve for controlling the admission of pressure fluid into said control cylinder or releasing the pressure fluid therefrom, a positioning motor, a positioning member controlled by said positioning motor, an operating connection between said positioning member and said valve for opening the latter to admit pressure fluid to said control cylinder, said operating connection being responsive to movement of said control rod for closing said valve upon admission of a predetermined quantity of pressure fluid to said pressure cylinder or for opening the valve upon predetermined movement of said positioning member, said control rod rotating with said drive shaft, and bearing means interposed between said control rod and said piston for rotatably relating the control rod to the piston.

6. In a variable capacity pump embodying a reciprocating pumping plunger, the combination of a drive shaft, an adjustable eccentric operatively connected with said plunger and having an opening therein through which said drive shaft is extended, coacting faces on said eccentric disc and said drive shaft for guiding the eccentric disc for movement transversely of the drive shaft for varying the throw of the eccentric to change the reciprocating stroke of said plunger, co-acting means on said eccentric disc and said drive shaft for limiting movement of the eccentric disc in one direction beyond its zero throw position and in another direction beyond its maximum throw position, and co-acting means on said control rod and said eccentric disc for shifting the eccentric disc through longitudinal movement of said control rod.

7. In a variable capacity pump having a plurality of reciprocating pumping plungers, the combination of a drive shaft, adjustable eccentric discs each operatively connected with one of the plungers and having opening therein through which said drive shaft is extended, said eccentric disc and the drive shaft having faces co-acting to guide the eccentric discs for movement transversely of the axis of rotation of the drive shaft

2,471,860

13

to vary the throw of the eccentrics, a control rod guided for longitudinal movement by said drive shaft, and co-acting rack teeth on said control rod and the eccentric discs for shifting the latter through longitudinal movement of said control rod.

8. In a variable capacity pump having a plurality of reciprocating pumping plungers, the combination of a drive shaft, adjustable eccentric discs each operatively connected with one of the plungers and having openings through which said drive shaft is extended, said eccentric discs and the drive shaft having faces co-acting to guide the eccentric discs for movement transversely of the axis of rotation of the drive shaft to vary the throw of the eccentrics, a control rod guided for longitudinal movement by said drive shaft, co-acting rack teeth on said control rod and the eccentric discs for shifting the latter through longitudinal movement of said control rod, and co-acting stop faces on said drive shaft and the eccentric discs for limiting movement of the latter in one direction beyond their zero throw positions and in another direction beyond their maximum throw position.

9. In a variable capacity pump embodying a reciprocating plunger, the combination of a hollow drive shaft having an opening intermediate its ends, an adjustable eccentric disc operatively connected with said plunger and having an opening through which said drive shaft is extended, means on said drive shaft for guiding said eccentric disc for movement radially of the axis of rotation of the drive shaft, a control rod movably guided in said drive shaft, and means on said control rod arranged angularly with respect to the axis of the drive shaft and co-acting with said eccentric disc through said opening for shifting the eccentric disc through longitudinal movement of the control rod for varying the throw of the eccentric.

10. In a variable capacity pump embodying a reciprocating pumping plunger, the combination of a tubular drive shaft having an opening in its perimeter, an adjustable eccentric disc operatively connected with said plunger, means on said drive shaft for guiding said eccentric disc for movement radially of the axis of rotation of said drive shaft, an eccentric cross bar attached to said eccentric disc, a control rod movably guided in said drive shaft, a rack fixed to said control rod, and formations on said eccentric cross bar and the rack engaging through said opening and angularly arranged so as to shift the eccentric disc radially of the axis of rotation of the drive shaft through longitudinal movement of said control rod, said rack and said eccentric cross bar keying the eccentric disc to the drive shaft for rotation therewith.

11. In a variable capacity pump, a cylinder, a reciprocating pumping plunger in said cylinder, a tubular drive shaft, an eccentric adjustably mounted on said drive shaft and operatively connected with said plunger, a control rod slidably guided inside said drive shaft in co-axial relationship therewith, co-acting means on said control rod and said eccentric for shifting the eccentric to different throw positions through relative movement of the drive shaft and the control rod, said co-acting means keying the control rod to the drive shaft for rotation therewith, a pressure fluid circuit including a control cylinder, a piston connected with the control rod and operating in said control cylinder, said control rod being rotatably related to said piston, a

14

pilot valve interposed in said fluid circuit for controlling the flow of pressure fluid to and from the control cylinder, a spring acting on said control rod to yieldingly hold the control rod in a neutral position and with the eccentric in a zero throw position, a floating lever connected with the pilot valve and having an operating connection with said control rod, and a positioning means connected with said floating lever for controlling the admission of pressure fluid to the control cylinder for moving the control rod against the tension of said spring or for releasing pressure fluid from the control cylinder, said operating connection being actuated through longitudinal movement of the control rod for adjusting the pilot valve to a closed position upon admission of a predetermined quantity of pressure fluid to the control cylinder.

12. In a variable capacity pump, a plurality of cylinders, reciprocating pumping plungers in said cylinders, variable throw crank means each operatively connected with one of said plungers, an adjusting means connected with said crank means to vary the throw thereof, a fluid pressure circuit, pressure fluid responsive means for operating said adjusting means, a valve interposed in said pressure fluid circuit for controlling the application of pressure fluid to said pressure fluid responsive means, and positioning means including a floating lever connected with said valve and said adjusting means for actuating the valve.

13. In a variable capacity pump, a plurality of cylinders, reciprocating pumping plungers in said cylinders, a tubular drive shaft having eccentric bodies fixed thereto and provided with openings in the planes of the eccentric bodies, eccentric discs each slidably mounted on one of said bodies for movement transversely of the drive shaft, eccentric straps each connected with one eccentric disc and one plunger, a control rod slidably longitudinally inside said drive shaft, angular means on said control rod and connected with the eccentric discs through said openings for shifting the eccentric discs relative to the eccentric bodies through movement of the control rod for varying the throw of the eccentric discs, and means for operating said control rod in predetermined increments.

14. In a variable capacity pump, a plurality of cylinders, reciprocating pumping plungers in said cylinders, a tubular drive shaft having eccentric bodies fixed thereto and provided with openings in the planes of the eccentric bodies, eccentric discs each slidably mounted on one of said bodies for movement transversely of the drive shaft, eccentric straps each connected with one eccentric disc and one plunger, a control rod slidably longitudinally inside said drive shaft, angular means on said control rod and connected with the eccentric discs through said openings for shifting the eccentric discs relative to the eccentric bodies through movement of the control rod for varying the throw of the eccentric discs, means for operating said control rod in predetermined increments, and plates attached to said eccentric discs and engaging the eccentric straps and said eccentric bodies to restrain the eccentric straps and said eccentric discs from relative movement longitudinally of said drive shaft.

15. In a variable capacity pump, a plurality of parallel cylinders, reciprocating plungers in said cylinders, an operating cross head connected to each of said plungers, operating eccentric straps connected to said cross heads, eccentrics mounted

in said eccentric straps, a driving shaft, said eccentrics adjustably carried by said driving shaft, and means shiftable longitudinally of said driving shaft to adjust the positions of the eccentrics relative to the driving shaft to vary the stroke of said cross heads for varying the throw of said plungers.

16. A variable capacity pump as claimed in claim 15 including pressure actuated means for shifting said longitudinally shiftable means, and pressure responsive means for controlling operation of said pressure actuated means.

17. A variable capacity pump as claimed in claim 15 including a pressure fluid circuit embodying a control cylinder, a piston connected to said longitudinally shiftable means and operating in said control cylinder, valve means for controlling the admission of pressure fluid into said control cylinder for moving said piston to move said longitudinally movable means, and means actuated by movement of said longitudinally movable means for closing said valve upon admission of a predetermined quantity of pressure fluid into said cylinder.

18. In a variable capacity pump, a plurality of parallel cylinders, reciprocating plungers in said cylinders, an operating cross head connected to each of said plungers, operating eccentric straps connected to said cross heads, eccentrics mounted in said eccentric straps, a driving shaft, crank bodies formed on said driving shaft, toothed cross bars carried by said eccentrics, toothed racks adjustably carried by said shaft and having their teeth meshing with the teeth of said cross bars, and means for shifting said toothed racks longitudinally of the axis of said driving shaft for individually adjusting said eccentrics to vary the stroke of said cross heads for varying the throw of said plungers.

19. A variable capacity pump as claimed in claim 18 wherein said driving shaft is hollow and is provided with radial openings through which said racks project, and a control rod extending longitudinally through said shaft and connected to said racks for shifting them.

20. A variable capacity pump as claimed in claim 18 wherein the teeth on said racks and the teeth on said cross bars extend at an acute angle to a plane perpendicular to the axis of said driving shaft.

21. In a variable capacity pump, a plurality of parallel cylinders, reciprocating plungers in said cylinders, an operating cross head connected to each of said plungers, operating eccentric straps connected to said cross heads, eccentrics mounted in said eccentric straps, a driving shaft, crank bodies formed on said driving shaft, toothed cross bars carried by said eccentrics, toothed racks adjustably carried by said shaft and having their

teeth meshing with the teeth of said cross bars, and means for shifting said toothed racks longitudinally of the axis of said driving shaft for individually adjusting said eccentrics to vary the stroke of said cross heads for varying the throw of said plungers, said driving shaft being hollow and provided with radial openings through which said racks project, and a control rod extending longitudinally through said shaft and connected to said racks for shifting them, pressure actuated means for shifting said control rod, and pressure responsive means for controlling operation of said pressure actuated means.

22. A variable capacity pump as claimed in claim 18 including a pressure fluid circuit embodying a control cylinder, a piston connected to said toothed rack shifting means and mounted in said control cylinder for reciprocation therein, the position of said piston in said control cylinder being controlled by admission of pressure fluid to the cylinder or the release of pressure fluid from the cylinder, a valve for controlling the admission of pressure fluid into said cylinder or for releasing the pressure fluid therefrom, a positioning motor, means actuated by said positioning motor, an operating connection between said positioning motor actuated means and said valve for opening the valve to admit pressure fluid into said control cylinder, and means operatively connecting said operating connection with said toothed rack shifting means for closing said valve upon the admission of a predetermined quantity of pressure fluid into said control cylinder.
